ABSTRACT OF THE DISCLOSURE

A system for storing a liquid hydrocarbon product in an underground cavern with an upper cavern for holding displacing fluid and a lower cavern for holding a liquid hydrocarbon product, disposed one above the other and a well bore from the surface of the earth to the upper cavern extending also into the lower cavern with means for withdrawing stored fluid from the lower cavern to the surface of the earth and at the same time allowing liquid from the upper cavern to flow through the well bore to the lower cavern without mixing with the liquid hydrocarbon product.

BACKGROUND OF THE INVENTION

This invention relates to a system for operating an underground fluid storage system wherein a liquid hydrocarbon product is stored in a storage cavern formed in a salt mass reservoir. This invention particularly relates to a system which uses brine as a displacing fluid and is particularly useful for underwater operations.

In recent years, the use of underground storage caverns has been widely adopted. These caverns are drilled, mined, dissolved or otherwise formed within a subterranean stratum. A common method of forming such caverns comprises dissolving with water sufficient salt from a salt deposit or bed to form a sizeable storage cavern.

The bores formed in the subterranean salt bed to produce the storage caverns are in communication with the surface of the earth by means of a number of pipes. In each bore is disposed at least one inlet pipe or outlet pipe for introduction and removal of stored liquid hydrocarbon and for introduction and removal of a displacing or heavier fluid, which fluid is usually saturated brine at the temperature and pressure of the cavern. Depending on the depth of the cavern and the material stored, the temperatures within the cavern may run as high as, e.g., several hundred degrees F., and the pressure in the cavern is usually several hundred pounds per square inch. One type storage cavern washed from a salt bed has a temperature of about 125 to 130° F. and, when storing liquid propane, the pressure runs about 400 to 500 p.s.i.

If a surface storage pit (or pits) is provided on the earth's surface where there is a lower temperature, for use with the displacing fluid (for example brine), there may be a problem of loss of salt at the surface. To counteract this, the removed brine may be diluted with water. When the cool dilute brine is pumped back into the cavern, it is unsaturated with respect to salt at the warmer cavern temperature and resaturates itself.

Thus, additional salt is dissolved from the cavern, and the cavern is thereby enlarged. Enlargement is detrimental both from a pumping and a handling consideration,

2

and also because leaking may develop when all the salt in a given location is dissolved.

To prevent enlargement of the cavern, additional reservoirs have been used with consequent additional bores for inlet and outlet piping. In the prior art practice, a plurality of separate bores in the earth are required to house a hydrocarbon supply and discharge line, a displacing fluid supply line and a gas supply line.

In this prior art practice, the hydrocarbon product and displacing fluid are in a first reservoir. The bottoms of the first and a second reservoir are connected by a conduit, so that the displacing liquid is at least partially stored in the second reservoir where it is covered by a cushion of gas under pressure. Separate bores for hydrocarbon product, displacing fluid and gas supply at discharge lines are provided.

The prior art practice of requiring a plurality of bores increases the cost of storing a hydrocarbon product in the earth, especially in off-shore sites where platforms must be initially constructed and equipment transported thereto.

SUMMARY OF THE INVENTION

Briefly described, this invention relates to a fluid storage system for storing a liquid hydrocarbon product beneath the surface of the earth in a storage cavern wherein a separate cavern at a higher elevation than the storage cavern is provided as a reservoir for brine at substantially formation temperature. The improvement comprises forming the caverns one above the other, with a well bore extending downward from the earth's surface into the upper cavern and from the upper cavern into the lower cavern. A product passageway is provided within the well bore extending from the earth's surface and terminating in the upper portion of the lower cavern. A separate gas passageway is provided in the bore extending from the earth's surface and terminating in the upper portion of the upper cavern. A brine conduit is provided within the bore intermediate the caverns, extending from the lower portion of the upper cavern and terminating in the lower portion of the lower cavern axially and centrally of the portion of the well bore and surrounded by the product passageway, and bypass means are provided within the well bore adjacent the lower portion of the upper cavern whereby brine from the upper cavern may pass into the brine conduit to displace hydrocarbon product from the lower cavern upwardly through the product passageway.

It is an object of the present invention to provide an underground cavern storage system for storing a liquid hydrocarbon product, wherein a single bore may be employed to service the underground reservoir.

It is another object of the present invention to provide an underground cavern storage system for storing a liquid hydrocarbon product, wherein the hydrocarbon product can be withdrawn without pumping.

It is also an object of the present invention to provide an underground storage system having a plurality of caverns spaced one above the other, at different levels, wherein the caverns are in communication with one another and with the earth's surface through a single bore.

It is an additional object of the present invention to provide a bypass construction in the piping in an underground bore, that will permit storage of a displacing fluid directly above the product zone of the reservoir, and at the same time, permit withdrawal of the product

liquid through the same bore without contamination of product liquid by displacement liquid.

Other objects and advantages of the present invention will become apparent to one skilled in the art, upon consideration of the accompanying disclosure.

BRIEF DESCRIPTION OF THE DRAWING

A more complete understanding of the invention may be had by reference to the drawing which is an elevation in partial section through a storage system showing a preferred arrangement of apparatus in accordance with the invention. For greater clarity, the full extent of the caverns have not been shown in the drawing.

DESCRIPTION OF THE PREFERRED EMBODIMENT

Referring to the drawing, a bore hole or well bore 2, is drilled from the surface of the earth 4, down through intervening formations such as a heterogeneous overburden 6, into an underground salt formation 8. The term "salt formation" is meant to include all formations containing a relatively large amount of soluble salt deposits, for example, water soluble salts of sodium, potassium and magnesium.

The earth's surface 4 may be either ground surface, or the floor of a body of water 5 as in off-shore locations. The bore 2 is initially formed by drilling a top section 10 of a large diameter in the overburden 6. A surface casing 12 (for example, having an 18-inch diameter) is then set into place and cemented at 14 to the formation. Where the overburden 6 is a solid, rocklike mass which does not crumble or fragmentate, so that it does not require lateral support, the surface casing 12 can be eliminated. The surface casing 12 is provided with a vent passage or line 16. The vent passage 16 is in communication with the atmosphere or a source of fluid at a pressure greater than atmospheric. The shaft 2, is then drilled from the bottom of the top section 10 into the salt formation 8 forming bore 18. A production casing or production passageway 20 of smaller diameter (for example, having a 16-inch diameter) and extending from above the surface casing 12 to the bottom of the bore section 18, is set into place within the surface casing 12. An annulus 12a is then joined about its outer periphery to the top edge of the surface casing 12 and about its inner periphery, to the outside of the production casing 20 by welding or other means. The annulus 12a, acts to space the production casing 20 away from the surface casing 12 and to form a seal between the production casing 20 and the surface casing 12.

An upper cavern 22 is formed in the salt formation 8 by methods which are well known and which include forcing a fluid in which salt is soluble (for example, water) against the sides of the shaft 2, at the desired elevation until a sufficient amount of salt is carried away in solution to form the desired cavity. The excess saturated salt solution is discharged at the surface through the line 16. Openings 24 are provided in the production casing 20 at the level of the upper cavern 22 to allow fluid to pass in and out of the upper cavern 22. The production casing 20 is then cemented at 26 to the wall of the bore in the shaft 2 below the upper cavern 22.

A lower cavern, like the upper cavern, is formed by similar well-known methods. The sizes of the upper cavern 22 and of the lower cavern 28 are dependent on the amount of hydrocarbon desired to be stored and the extent of the salt mass.

A bypass 30, suitably of the type described on page 3782 of the 1968-69 Composite Catalog of Oil Field Equipment & Services, Gulf Publishing Company, Houston, Tex. and described therein as a "New Otis Sliding Side-Door Dual Cross-Over Assembly," is then lowered into the production casing 20 until it is adjacent the upper cavern 22. Upper and lower annular packing rings 32 and 34, respectively, are set permanently into place

against the inside surface of the production casing 20, above and below the bypass 30. The bypass 30 is thus anchored in place and a fluid seal is formed thereby to prevent contact between the fluid in the upper chamber 22 and the fluid in the production casing 20, outside the bypass 30. The setting and sealing of annular packing rings 32 and 34 in the production casing 20 is a well known art. As a practical matter, the lower annular packing ring 34 is set into the production casing 20 prior to the bypass 30 being lowered therein.

An open-ended conduit 36 is lowered into the shaft 2 until the bottom end is just above the bottom of the lower cavern 28, where it is set into place. The length of the conduit 36 is such that in this position, the top end is just above the top of the upper cavern 22. Openings 36a are provided in the conduit 36 adjacent openings 24 in the production casing 20 to communicate the upper cavern 22, with the bypass 30.

Exclusive passage of the fluid from the upper cavern 22 to the lower cavern 28 is provided by the openings 24, the bypass 30, the openings 36a, and the conduit 36. The top end of the conduit 36 is sealed with a plug 38, preventing fluid in the conduit 36 from escaping therefrom and intermixing with fluid in the production casing 20.

The fluid in the lower cavern 28 is introduced therein or withdrawn therefrom, through an exclusive passage. This passage includes a lower annular passage 20a, defined by the inside of the production casing 20 and the outside of the conduit 36, passages 40 in the bypass 30, and the inside of the production casing 20, above the conduit 36.

The production casing 20 is sealingly connected to a pipe 42, above the surface 4, in which is disposed a shut-off valve or other valve means 44, to control the flow of fluids therethrough.

The operation of the system for storing liquid hydrocarbon product in the underground storage cavern described above with brine as displacing fluid, is described as follows. A fuel line containing liquid hydrocarbon under pressure is connected to the pipe 42. Valve 44 is opened. The liquid hydrocarbon is pumped from the source through the production casing 20, the passages 40 and the lower annular passage 20a into the lower cavern 28. Brine in the lower cavern 28 is displaced by the liquid hydrocarbon and flows up out of the lower cavern 28 through the conduit 36 and bypass 30 via the openings 36a in the conduit 36, and through the openings 24, into the upper cavern 22. Excess brine in the upper cavern 22 is forced up through an annular passage 20b between the production casing 20 and the main section 18, and annular passage 20c between the production casing 20 and the surface casing 12, out through the line 16.

When the preestablished volume of liquid hydrocarbon product storage space in the lower cavern 28 is reached, an operator closes the valve 44, stopping the flow of liquid hydrocarbon product from entering the lower cavern 28. The volume of liquid hydrocarbon product stored can be substantially commensurate with the volume of the lower cavern 28 or any lesser amount. When the lower cavern 28 is not substantially filled with stored liquid hydrocarbon, a residual amount of brine remains in the lower cavern 28.

To withdraw the stored liquid hydrocarbon, valve 44 is opened, and the stored liquid hydrocarbon is displaced by the brine flowing from the upper cavern 22 through the bypass 30 and the conduit 36 to the lower cavern 28. The hydrostatic pressure of the brine may be, in some instances, sufficient to force the liquid hydrocarbon up to the surface without the need for pumping. The hydrocarbon flows via the lower annular passage 20a, the passages 40, the bypass 30 and the production casing 20 to the line 42 at the earth's surface. The brine in the upper cavern 22 may be displaced with gas under pressure. Preferably the spacings of the caverns are such that the stored

liquid hydrocarbon may be displaced by the brine without the necessity for pumping either hydrocarbon or air.

In order to initiate and sustain the flow of the liquid hydrocarbon product to the surface without pumping hydrocarbon product or gas, the vertical distance between the upper cavern 22 and the lower cavern 28 must be greater than the product of the vertical distance between the surface and the lower cavern 28 and a fraction defined by the specific gravity of the liquid hydrocarbon product divided by the specific gravity of the brine.

Generally, the most economical displacing fluid is brine, which is readily available. However, any fluid which is immiscible with and has a sufficiently greater density than the liquid hydrocarbon to be stored, can be used as the displacing fluid.

With brine and crude oil, having respective specific gravities of 1.2 (at a depth of 2000 feet) and 0.9 as components of the system, the product of the height of the brine in conduit 36 and the specific gravity of brine divided by the specific gravity of crude oil

$$\left(\text{i.e., } \frac{1.2}{0.9} \right)$$

must be greater than the height of the crude oil in the lower annular passage 20a and production casing 20, the lengths being similar units. In other words, when the product of the height of brine between the bottom of the upper cavern 22 and the top of the lower cavern 28 and the fraction defined by dividing the specific gravities of brine with crude oil, is greater than the height of crude oil between the valve 44 and the top of the lower cavern 28, the crude oil may be recovered from cavern 28 without pumping.

Following are specific examples of the depth, volume and arrangements of caverns made according to the disclosure of the present invention with various liquid hydrocarbons being stored in a fluid storage system using brine as the displacing fluid.

EXAMPLE I

The bottom of the upper cavern 22 is 500 feet from the surface. The volume of both the upper and lower cavern 22 and 28, is each 560,000 cubic feet. The vertical distance between the bottom of the upper cavern 22 and the bottom of the lower cavern 28 is 2500 feet. In the lower cavern 28, 25° API crude oil is stored. The diameter of the production casing 20 is 24 inches, and the diameter of the surface casing is 36 inches. The diameter of the liner 36 is 13½ inches. The minimum pressure at valve 44 during storage operations would be 121 pounds per square inch.

EXAMPLE II

The bottom of the upper cavern 22 is 1000 feet from the surface. The volume of both the upper and lower cavern 22 and 28, is each 560,000 cubic feet. The vertical distance between the bottom of the upper cavern 22 and the bottom of the lower cavern 28 is 2000 feet. In the lower cavern 28, liquid propane is stored. The diameter of the production casing 20 is 24 inches, and the diameter of the surface casing is 36 inches. The diameter of the liner 36 is 13½ inches. The minimum pressure at valve 44 during storage operations would be 381 pounds per square inch.

EXAMPLE III

The bottom of the upper cavern 22 is 500 feet from the surface. The volumes of both the upper and lower caverns 22 and 28 are each 560,000 cubic feet. The vertical distance between the bottom of the upper cavern 22 and the bottom of the lower cavern 28 is 2500 feet. In the lower cavern 28, 38° API crude oil is stored. The diameter of the production casing 20 is 24 inches, and the diameter of the surface casing is 36 inches. The diam-

eter of the liner 36 is 13½ inches. The minimum pressure at valve 44 during storage operations would be 211 pounds per square inch.

The above examples show various density crude oils being stored in an underground storage reservoir built according to the disclosure of the present invention, and withdrawn at will. Although the present invention is particularly useful for the storage of liquid hydrocarbon product or crude oil in offshore production areas, this invention is not limited to such areas or such products. Various fractions of hydrocarbons, such as liquid propane, may be stored in the manner described.

There is no requirement that the intended cavern of the present invention be in a salt dome. Natural or artificially produced caverns may be used, so long as the walls are impervious to the stored material.

Obviously, many modifications and variations of the invention, as hereinbefore set forth, may be made without departing from the spirit and scope thereof, and therefore only such limitations should be imposed as are indicated in the appended claims.

I claim:

1. In a fluid storage system for storing a liquid hydrocarbon product beneath the surface of the earth in a storage cavern wherein a separate cavern at a higher elevation than said storage cavern is provided as a reservoir for brine at substantially formation temperature, the improvement which comprises:

- (a) forming said caverns one above the other, with a well bore extending downward from the earth's surface into said upper cavern and from said upper cavern into said lower cavern,
- (b) providing a product passageway within said well bore extending from said earth's surface and terminating in the upper portion of said lower cavern,
- (c) providing a separate gas passageway in said bore extending from said earth's surface and terminating in the upper portion of said upper cavern,
- (d) providing a brine conduit within said bore intermediate said caverns extending from the lower portion of said upper cavern and terminating in the lower portion of said lower cavern, axially and centrally of said portion of said well bore and surrounded by said product passageway, and
- (e) providing bypass means within said well bore adjacent the lower portion of said upper cavern whereby brine from said upper cavern may pass into said brine conduit to displace hydrocarbon product from said lower cavern upwardly through said product passageway.

2. A fluid storage system as described in claim 1, wherein said product passageway is substantially concentric with said bore and said gas passageway comprises an annular conduit surrounding said product passageway.

3. A fluid storage system as described in claim 1, wherein said well bore is provided with a casing from the surface of the earth to the upper portion of said upper cavern, said casing forming the outer wall of said gas conduit.

4. In a fluid storage system for storing a liquid hydrocarbon product beneath the surface of the sea floor in a storage cavern wherein a separate cavern at a higher elevation than said storage cavern is provided as a reservoir for brine at substantially formation temperature, the improvement which comprises:

- (a) forming said caverns one above the other with a well bore extending downward from said sea floor surface into said upper cavern and from upper cavern into said lower cavern,
- (b) providing a product passageway within said well bore extending from above the sea surface and terminating in the upper portion of said lower cavern,
- (c) providing a separate gas passageway in said bore extending from above said sea surface and terminating in the upper portion of said upper cavern,

- (d) providing a brine conduit within said bore intermediate said caverns extending from the lower portion of said upper cavern and terminating in the lower portion of said lower cavern axially and centrally of said portion of said well bore and surrounded by 5 said product passageway, and
- (e) providing bypass means within said well bore adjacent the lower portion of said upper cavern whereby brine from said upper cavern may pass into said brine conduit to displace hydrocarbon product from said lower cavern upwardly through said product passageway.
